D-HANDLE

Filed April 28, 1928

James H. Wily

INVENTOR

BY

Prindle, Wright, Dean & Beau ATTORNEYS

UNITED STATES PATENT OFFICE

JAMES H. WILY, OF BETHLEHEM, PENNSYLVANIA

D-HANDLE

Application filed April 28, 1928. Serial No. 273,502.

One object of the invention is to provide a D handle member which will have a simple and effective locking engagement between the sides of the handle and its grip, to prevent turning of the grip during use, and avoid unduly weakening the same.

Another object is to provide a simple and effective lock for the abutting ends of the part of the handle member which is bent around into annular shape to form a socket adapted to receive the handle extending from the tool in connection with which the D handle is used.

Further objects and advantages of the invention will be in part obvious and in part specifically pointed out in the description hereinafter contained which, taken in conjunction with the accompanying drawings, discloses a preferred embodiment of the invention; such embodiment, however, should be considered merely as illustrative of its principles. In the drawings—

Fig. 1 is a plan view of a handle constructed in accordance with the invention with certain parts cut away.

Fig. 2 is a side view of the handle shown in Fig. 1.

Fig. 3 is a detail showing portions of the parts which form the locking engagement between the side arms of the handle and the grip member.

The handle has a socket 1 and side arms 2, the above parts being usually formed out of a sheet metal blank having its base bent around into annular shape with abutting ends 3 and 4, to form the socket 1 and tongues or fingers which are shaped to form the side arms 2. A handle grip member 5, usually of wood, is mounted between the side arms 2 and usually held in place by means of a pin 6 passing through the grip member and side arms, and having its opposite ends riveted over against the side arms.

In accordance with one feature of the present invention, an inwardly projecting tongue 7 is struck up adjacent the end of one or both of the side arms 2, this tongue being of substantial width and projecting into the end of the grip member 5 in such manner that rotation of the grip member with re-

spect to the side arms is effectively prevented. Preferably the ends of grip member 5 are provided with slots 8 to receive the tongues 7 and thereby reduce the likelihood of splitting the grip member when the tongues are inserted. In the illustrated embodiment of the invention, the whole end of each of the side arms 2 is shown as struck out or bent over to form the tongues 7.

Where a pin 6 is employed in connection with the grip member, the tongues 7 will be first engaged with the grip member and the pin then put in place and its ends riveted over.

A lock of the above nature is simple and inexpensive to construct and assemble, and effectually prevents the grip member from twisting without imposing undue splitting strains thereon.

In accordance with another feature of the invention the opposed ends 3 and 4 of the socket 1 are provided with a complementary recess 9 and projection 10 and the adjacent edges of such recess and projection are provided with one or more sets of opposed notches 11 and 12 respectively, whereby a locking pin member 13 may be inserted into the hole formed by each pair of opposed notches 11 and 12, in such manner as to prevent separation of the opposed ends 3 and 4 of the socket. The pin 13 may be, for example, a nail or screw, which passes into the tool handle enclosed by the socket, or a rivet which passes all the way through to the opposite side of the socket, as desired.

While a specific form of the invention has been described, it should be understood that many changes may be made therein, without departing from its principles as defined in the appended claims.

I claim:

1. A D handle member having substantially flat side arms, a grip member interposed between said side arms and at least one side arm having a tongue of substantial width adjacent its end and projecting into the corresponding end of the grip member.

2. A D handle having substantially flat side arms, a grip member interposed between said side arms, a holding pin passing through

said grip member and side arms, and the end of at least one of said side arms being bent over to form a tongue projecting into the corresponding end of the grip member so as to prevent rotation of the grip member.

3. A D handle member having side arms, a grip member interposed between said side arms and at least one side arm having a flat tongue of substantial width adjacent its end and projecting into the corresponding end of the grip member, the last mentioned end of the grip member having a slot adapted to receive said tongue.

4. A D handle member having side arms, a grip member interposed and held between said side arms and formed with a groove in its end, a horizontal holding pin passing through said grip member and side arms, and at least one side arm having a flat tongue of substantial width at its end and received by the groove in the grip member to prevent rotation of the grip member.

5. A D-handle member having a socket formed of a plurality of sections having complementary interlocking parts, side arms extending from said socket, said side arms being provided with flange means adapted to project into and prevent rotation of a grip member.

30 6. A D-handle including a socket member, flat side arms extending from said socket member, each side arm being provided with a flange at its end, a grip member provided with grooves to receive said flanges.

35 7. A D-handle member having a socket formed of a plurality of sections having complementary interlocking parts, and flat side arms extending from said socket, one of said arms being provided with a flange at the end thereof, said flange being adapted to project into a groove formed in a grip member.

8. A D-handle member having substantially flat side arms, each side arm being provided with a flange at right angles to the end of the side arm, said flanges being of substantially the same width as the side arms, a grip member formed with horizontal slots in its ends to receive said flanges and a pin passing through said side arms and said grip member.

50 In testimony that I claim the foregoing, I have hereunto set my hand this 4th day of April, 1928.

JAMES H. WILY.
